DESIGN FOR A DENTAL FLASK

Edward Handler, Irvington, N. J.

Application August 4, 1934, Serial No. 52,813

Term of patent 14 years

To all whom it may concern:

Be it known that I, EDWARD HANDLER, a citizen of the United States, and a resident of Irvington, in the county of Essex and State of New Jersey, have invented a new, original, and ornamental Design for a Dental Flask, of which the following is a specification, reference being had to the accompanying drawing, forming part thereof.—

Figure 1 is a perspective view of a dental flask showing my new design, and

Figure 2 is a side elevation thereof viewing the flask from the side opposite that facing the observer in Figure 1.

I claim:

The ornamental design for a dental flask as shown.

EDWARD HANDLER.
